UNITED STATES PATENT OFFICE.

HUGH W. FELLOWS, OF CAHUENGA, CALIFORNIA, ASSIGNOR TO FELLOWS DIRECT POWER TRANSMISSION COMPANY, A CORPORATION OF ARIZONA TERRITORY.

SAFETY STARTING-CRANK.

No. 921,098.

Specification of Letters Patent. Patented May 11, 1909.

Application filed October 11, 1907. Serial No. 397,028.

To all whom it may concern:

Be it known that I, HUGH W. FELLOWS, a citizen of the United States, residing at Cahuenga, county of Los Angeles, State of California, have invented a new and useful Safety Starting-Crank, of which the following is a specification.

This invention relates to a safety starting crank which is adapted for cranking internal combustion engines, in starting them, and the object of the invention is to provide a starting crank which will prevent injury to the user thereof.

In cranking internal combustion engines, a premature ignition often occurs which throws the crank suddenly backward with such suddenness and force that the arm of the person operating the crank is broken or the person otherwise injured. A careful person in cranking will usually retard the spark of his engine before cranking and will endeavor to regulate his crank movement so that he will not push on the crank but will pull upwardly on the crank as the piston of the engine approaches the ignition point, thus minimizing the danger of breaking his arm, should the engine fire prematurely and start backward while he was pulling up, as then the crank would be forced out of his hand in a direction away from his arm. In spite of these precautions, however, accidents are of frequent occurrence, and it is to absolutely prevent such accidents that this device is designed, it being so constructed that no skill is required in operating it, as the crank may be turned in its circle by pulling up on it through one-half of its stroke and then pushing down through the other half of its stroke.

The invention, briefly, comprises means for maintaining operative relation between the crank and engine shaft so long as the resistance of the engine shaft does not appreciably exceed its normal resistance due to compression, friction, etc., but which operative relation immediately ceases upon a sudden excess of resistance of the engine.

A further object of the invention is to provide means for adjusting the crank so that it may be set to release at any desired degree of resistance. The crank may be applied and regulated to suit varying compressions of engines of a given make, or to suit various makes of engines.

The accompanying drawings illustrate the

invention and referring thereto:—Figure 1 is a rear elevation of the crank; partly in section, on line x^1-x^1 Fig. 2. Fig. 2 is a longitudinal vertical section through the crank on line x^2-x^2 Fig. 1. Fig. 3 is a view similar to Fig. 1, showing the crank at an angular position in which back firing often occurs, and illustrating the position of the parts immediately after the operative relation between the crank and engine has ceased. 65

In the preferred embodiment of the invention, 1 designates the crank arm having a hub 2. Mounted in the hub 2 and adapted to have revoluble movement therein is a socket 3 which is held against longitudinal movement in the hub by means of a screw 4 which engages an annular groove 5 in a socket. The socket 3 is adapted to receive the reduced portion 6 of the engine shaft 7 and the inner end of socket 3 has a spiral notch 8 which is adapted to engage a similar spiral notch 9 formed on the engine shaft 7. This construction for securing engagement between the socket and engine shaft is one well known in the art, which allows the engine shaft to run ahead of the crank when the engine starts, but as the specific arrangement employed for this particular purpose is immaterial to the present invention, any other preferred device for accomplishing this purpose may be employed. 85

The socket 3 is provided with a recess 10 forming an abutment 11, and pivoted at 12 to the crank arm 1 is a release lever 13 having a detent 14 which normally lies in the recess 10 and bears against the abutment 11 thus preventing revoluble movement of the socket in the hub. The release lever 13 at its upper end is provided with a hook or transverse fork 15. A handle 16 is secured in the upper end of the crank arm 1 and is centrally drilled to receive a spring bolt 17. The outer portion of the handle 16 is counterbored to receive a coil spring 18 which bears against a nut 19 screwed on the end of the bolt. The bolt 17 is provided with a head 20 and the fork 15 of the release lever 13 is normally received back of the head 20 by straddling the bolt 17, and the spring 18 serves to hold the bolt retracted so that its head 20 yieldingly holds the upper end of the release lever 13 close to the crank arm 1. A low abutment 21 is provided at the upper end of the crank arm 1, back of which the release lever 13 is held normally by means of the bolt head 20, 110

but the release lever 13 is permitted a sufficient lateral movement at its upper end to clear the abutment 21 when allowed to do so by the bolt head 20 yielding outwardly. In order to restrict longitudinal movement of bolt 17, it is provided with a slot 22 into which a pin 23 projects. When the release lever 13 is free from the bolt 17, the spring 18 will contract but will only move the bolt head inwardly a slight distance allowed by slot 21 and the fork 15 of the release lever is tapered so that it may readily be swung back behind the head 20 in restoring it to normal position.

It will be noticed that a considerable force will be required to act against the detent 14 to tilt the release lever 13 on its pivot 12 to overcome the detachable engagement of the upper end of the release lever. Obviously, if the tension of the spring 18 is considerable, a relatively great pressure will be required against detent 14 to cause the release lever to move laterally against the tension of spring 18 and slip over the abutment 21. The spring 18 should be adjusted such that it will prevent the normal resistance of the engine, due to compression, friction, inertia, etc., from disengaging the release lever. Thus in operating the crank, should the engine backfire it will impart a sudden blow of great force to the detent 14 which will instantly disengage the release lever 13 and the latter will fly away from the crank arm 1, as shown in Fig. 3, thereby disengaging the crank from its socket 3 and permitting the socket 3 to revolve backward with the engine shaft. This automatic disengagement of the release lever 13 relieves the crank arm from the shock of back firing, the only extra force imparted to the hand of the operator being that small amount of excess force necessary to cause compression of spring 18 in the disengaging movement of the release lever. As the spring need be set for but little more than the power required to normally crank the engine, the extra pressure on the hand is not in the least injurious, and in fact is scarcely perceptible in practice.

The crank may be provided with the socket 3 as shown, or any other desired equivalent therefor, and as this part may readily be taken from the crank by removing screw 4, the socket may be readily rebored, or otherwise altered, to fit or coact with the end of the engine shaft with which the crank is to be used.

What I claim is:—

1. A safety starting crank comprising a crank arm, a circumferentially grooved socket mounted therein, a pin in said arm projecting into said groove, a release lever on the crank arm normally locking the

socket, yielding means for normally preventing movement of the release lever, and means for regulating the tension of the yielding means. 65

2. A safety starting crank comprising a crank arm, a socket mounted therein, a release lever on the crank arm normally locking the socket, an abutment on the crank arm over which the release lever is movable, and yielding means for normally holding the release lever back of the abutment. 70

3. A safety starting crank comprising a crank arm, a socket mounted therein and having a shoulder, a release lever pivoted to the crank arm and having a detent normally engaging said shoulder, an abutment on the crank arm over which the release lever is movable, and a spring bolt normally holding the release lever back of the abutment. 75 80

4. A safety starting crank comprising a crank arm, a socket mounted therein and having a shoulder, a release lever pivoted to the crank arm and having a detent normally engaging said shoulder, an abutment on the crank arm over which the release lever is movable, and a spring bolt normally holding the release lever back of the abutment, the upper end of the release lever having a fork, 90 and the spring bolt having a head behind which the fork is received. 95

5. A safety starting crank comprising a crank arm, a socket mounted therein and having a shoulder, a release lever pivoted to the crank arm and having a detent normally engaging said shoulder, an abutment on the crank arm over which the release lever is movable, a spring bolt normally holding the release lever back of the abutment, a handle 100 on the crank arm housing the spring bolt, a nut on the end of the spring bolt, and a spring within the handle bearing against the nut. 105

6. A safety starting crank comprising a crank arm, a socket mounted therein and having a shoulder, a release lever pivoted to the crank arm and having a detent normally engaging said shoulder, an abutment on the crank arm over which the release lever is movable, a spring bolt normally holding the release lever back of the abutment, a handle on the crank arm housing the spring bolt, a nut on the end of the spring bolt, a spring within the handle bearing against the nut, the spring bolt having a slot, and a screw 110 115 projecting into the slot for limiting the sliding movement of the spring bolt.

In testimony whereof, I have hereunto set my hand at Los Angeles, California, this 4th day of October, 1907.

HUGH W. FELLOWS.
